UNITED STATES PATENT OFFICE.

CHESTER A. BARNES, OF BLUE GRASS, IOWA.

FEEDING-TROUGH.

1,276,610.

Specification of Letters Patent. Patented Aug. 20, 1918.

Application filed January 31, 1918. Serial No. 214,693.

To all whom it may concern:

Be it known that I, CHESTER A. BARNES, a citizen of the United States, residing at Blue Grass, in the county of Scott and State of Iowa, have invented certain new and useful Improvements in Feeding-Troughs, of which the following is a specification.

This invention relates generally to feeding devices for animals, and is directed particularly to hog troughs, being an improvement upon the device disclosed in my Patent #1,234,117.

An object of the invention is to provide a feeding device constructed so as to permit of a number of animals feeding therefrom at one time, having a vertically movable hood to move toward or away from the feeding trough, and embodies improved means for controlling the movements of the said hood.

Another object is to provide a feeding device of the character stated which is capable of being quickly and easily operated when it is required to move the hood, and which is equipped with improved means for maintaining the hood in adjusted position.

A still further object of the invention is to provide an improved trough for the reception of food, which will be of inexpensive construction and which has its various parts so arranged as to be readily accessible, and which is at all times protected from rain, sleet, snow and the like.

With these objects in view, together with others which will appear as the description proceeds, the invention resides in the novel formation, combination, and arrangement of parts, all as will be described more fully hereinafter, illustrated in the drawings, and particularly pointed out in the claims.

In the drawings:—

Figure 1 is a side elevation of a feeding trough constructed in accordance with the invention,

Fig. 2 is a top plan view of the trough,

Fig. 3 is a transverse sectional view taken upon line 3—3 of Fig. 1.

Fig. 4 is an enlarged plan view of the trough,

Fig. 5 is a detail view illustrating a part of the mechanism used in raising and lowering the hood,

Fig. 6 is a fragmentary side elevation of the pawl and ratchet mechanism for holding the hood in adjusted position, and

55

Fig. 7 is a detail perspective view showing the device employed for controlling the degree of movement of the hood.

Referring now more particularly to the drawings, 8 represents generally the base 60 of the improved feeding device, being formed of a pair of spaced angle irons held spaced apart the proper distance by suitable cross members 9. This base has projecting upwardly from one end thereof the uprights 65 10, the latter being reinforced by angularly disposed base members 11.

The base of the feeding device includes a frame indicated at 12, coextensive with the main base 8, and being spaced above the latter a short distance and held rigidly thereto by the connecting members 13. This frame

70

has arranged therein a tank or receptacle 14, the latter being firmly affixed at its sides to bars constituting the frame 12, and receives the removable trough 15. This trough is slightly smaller than the receptacle 14, and is hinged as at 16 to one of the longitudinal bars 12 of the frame. The trough is thus capable of being swung into or out 80 of the tank or receptacle 14, and the outwardly protruding flanges on the upper end of the trough fit over the upper edges of the tank or receptacle 14 so as to prevent food or other matter passing into the said receptacle. As the receptacle 14 is rigidly secured to the frame and base of the device, ice or mud working under the receptacle will be prevented from interfering with the free movement of the trough 15.

90

Hinged as at 18 to one of the longitudinal edges of the trough 15, and preferably opposite to the side of the trough which is hingedly connected with the frame 12, is a frame 19. This frame comprises a pair of 95 spaced longitudinal side members, connected by laterally extending rails or bars 20, the latter being arranged in spaced parallel relation throughout the length of the frame. These bars are of a length equal to the width 100 of the trough 15, and the free end of the hinged frame 19 is adapted to move thereon and rest upon the upper edge of the said trough. Turn buttons 21 are arranged upon

the free end of the hinged frame, and are adapted to engage under the retaining devices 22 carried by the trough, whereby the frame may be held firmly in lowered position. It will be observed that the transverse bars 20 are spaced such distance apart as will permit of animals comfortably feeding between the same. When it is desired to gain access to the trough for cleaning purposes, the turn buttons 21 are unlatched from the keepers 22, and the dividing frame 19 may be swung backwardly. To dump the trough 15 it is but necessary to swing the same upon its hinges 16, whereupon the 15 said trough will be inverted.

The trough 15 is supplied with food through a spout or outlet 23, the latter being in communication at one end with one end of the trough, and at its opposite end 20 with a hopper 24. This hopper is preferably disposed beyond one end of the device, and in such position as to be readily accessible to an attendant. Food delivered to the hopper 24 will pass through the spout 25 23 and into the feed trough.

The vertically movable hood is indicated generally at 25, and comprises a frame constituting longitudinal bars 26 of a length substantially equal to the frame 12, and also 30 being of the same width as the said frame. The hood frame is closed by a plate 27, which terminates inwardly from one end of the said frame. The hood is supported at its ends upon the upper ends of links 28 35 pivoted at their lower ends as at 29 to the frame 12, and the hood is confined between guides 30 arranged in spaced relation upon the sides and projecting upwardly from the frame 12. The hood 25 is adapted to move 40 upwardly or downwardly, and when in the last named position fits close over the upper end of the feed trough, preventing animals from having access thereto. When it is desired to allow the animals to eat 45 from the trough, the frame is raised by moving the same rearwardly, it being understood that the link arrangement 28 causes the frame to ride upwardly when rearward movement is delivered thereto.

50 Rotatably mounted upon the upper ends of the uprights 10 and extending transversely of the feeding device is a shaft 32 provided at one end with the crank 33 to enable the said shaft to be rotated. This 55 shaft is provided intermediate its ends with a gear 34, having flanges 35 projecting outwardly from its ends. This gear is in mesh with a rack bar 36 formed upon the interior surface and upon one side of a closed 60 pitman 37. The upper and lower rails of the pitman are confined between the flanges 35 at the ends of the gear, so that the pitman is held in proper position upon the gear at all times. One end of the pitman is 65 pivotally secured to an upstanding post 38

adjacent one end of the hood 25, and it is obvious that by rotating the shaft 32, the gear 34 will cause the pitman to move over or away from the feeding device accordingly as the shaft is rotated, whereupon the 70 hood will be swung upon the supporting links 28. The shaft is provided adjacent one end with a ratchet wheel 39, engaged with which is a pawl 40 for holding the ratchet wheel against rotation in one direction. This pawl and ratchet arrangement holds the hood in proper adjusted position. 75

Associated with the pitman 37 is a clamp member for limiting the rearward movements of the pitman. This clamp comprises 80 a pair of bars 41 having inwardly projecting arms 42 at their extremities adapted to engage over the pitman at the upper and lower edges thereof. These bars are connected by a threaded stem 43 which extends 85 through the space between the said upper and lower bars of the pitman, and has threaded upon one extremity a wing nut 44. The clamp member may be moved longitudinally of the pitman, and when it is desired to 90 hold the same against movement, the wing nut is tightened, thereby binding the clamping bars firmly against the sides of the pitman. This clamping member forms an abutment to engage with the gear 34, 95 and it will be understood that when so engaged, the pitman will be held against further rearward movement.

To prevent the animals passing over the hood when the latter has been lowered upon the feeding device, a fence 45 is provided. This fence rises upwardly from the longitudinal edges of the frame constituting the hood, and one end also of the said frame is 100 closed. The fences are of a height substantially equal to the distance between the frame 12 and the upper ends of the guide posts 30, and will prove of sufficient height to prevent animals climbing upon the top of the hood. 105

110 From the foregoing it is obvious that I have provided a feeding device which will prove thoroughly efficient and practical for its purposes, and which may be easily operated to permit of the animals feeding therefrom or to preclude the animals having access to the trough. It will be observed that the bottom plate 27 of the hood terminates short of one end of the hood frame, so that when the latter is lowered, it will 115 not interfere with the supply trough or spout 23. It is thus possible to supply the trough with food when the hood is in lowered position, as the animals will not have access to the trough until the said hood is 120 raised. When it is desired to permit of small animals feeding from the trough, and to prevent their feeding interfered with by larger animals, the shaft 32 is rotated only 125 so much as will raise the hood 25 a short 130

distance above the upper edge of the trough, such distance being sufficient to permit of the entrance of the heads of the small animals between the same and the trough.

5 When, however, it is desired to permit all animals to feed from the device, the shaft is rotated so as to move the hood to the limit of its upward travel.

While the present is a disclosure of what 10 is believed to be the preferred embodiment of the invention, it is to be understood that the invention is not limited thereto, as various changes in the minor details of construction, proportion, and arrangement of 15 parts may be resorted to if desired without departing from the spirit of the invention as defined by the appended claims.

I claim:—

1. In a device of the class described, a 20 base, a feed receptacle in said base, an upright at one end of said base, a hood, links connecting said base and hood, a shaft on said upright, a gear on the said shaft, a rack bar in mesh with said gear and being connected at one end with said hood, and means for rotating said shaft.

2. In a device of the class described, a 25 base, a feed receptacle in said base, a shaft at one end of said base, a hood adapted when moved in one position to cover said trough, links connecting said base and hood, a gear on said shaft, flanges on the ends of said gear, the said rack bar being connected at one end with said hood and being in mesh

with said gear and confined between said 35 flanges, and means for rotating said shaft.

3. In a device of the class described, a base, a feed receptacle in said base, guide posts extending upwardly from said base, a hood in said guides capable of moving in a vertical plane, a shaft at one end of said base, a rack bar adapted to be moved upon rotation of said shaft, the said rack bar being connected with one end of said hood, and links connecting the ends of said hood with 45 said base.

4. In a device of the class described, a base, a feed receptacle in said base, uprights at one end of said base, guide posts extending upwardly from said base and in spaced 50 relation to each other, a hood movable between said posts, links connecting the ends of said hood to said base, a shaft on said uprights, a gear on said shaft, flanges projecting from the ends of said gear, a rack 55 bar having a closed side and in mesh with said gear and being confined between said flanges, a pawl and ratchet mechanism between said uprights and shaft, the said rack bar being connected to said hood and means 60 for rotating said shaft.

In testimony whereof I affix my signature in presence of two witnesses.

CHESTER A. BARNES.
